UNITED STATES PATENT OFFICE.

WILLIAM S. PLUMMER, OF SAN JOSÉ, CALIFORNIA.

VEGETABLE-PRESS.

SPECIFICATION forming part of Letters Patent No. 245,556, dated August 9, 1881.

Application filed February 5, 1881. (No model.)

To all whom it may concern:

Be it known that I, WILLIAM S. PLUMMER, of San José, in the county of Santa Clara and State of California, have invented a new and useful Improvement in Vegetable-Presses, of which the following is a specification.

My improvements relate to apparatus for pressing potatoes and other vegetables, and at the same time laying the pressed material upon trays in a convenient form for drying.

My invention consists in a press-box and follower of novel construction, and in combination therewith a tray fitted to move on a track beneath the press-box, as hereinafter described and claimed.

In the drawings, Figure 1 is a front elevation of the machine with the tracks in transverse section. Fig. 2 is a plan view of the same. Fig. 3 is a vertical section on line $x-x$ of Fig. 1. Fig. 4 is an end elevation; and Fig. 5 is a partial plan view of a tray.

Similar letters of reference indicate corresponding parts.

A is the press-box, supported by side standards, a a , from the string-pieces b b of the tramway, which will extend to the drying-house. The box A is made of wood or metal of suitable shape and size, and is formed at its top with a hopper-shaped extension, c , for convenience in filling the box. The bottom d of the box inclines downward to a concave plate, e , that is secured between the bottom d and the lower front edge of the box, and in the plate e is a row of openings, e' , separated by partitions d' , secured to bottom d .

f is a concave slide-plate supported in slide-ways at its ends, and connected with arms f' , that project from a rock-shaft, g , which is sustained at the front of the press-box. On the end of shaft g is fixed a lever, g' , for use in moving the slide f to open or close the apertures e' .

B is the platen or follower, sustained by rack-bars h h , that rise vertically from its ends, and engaging with pinions i i , that are on a shaft, i' , which is sustained in the standards a of the press-box.

k are friction-rollers carried by a shaft, k , and bearing on the back of racks h , so that the racks are retained in contact with pinions i .

l is the driving-shaft, having a crank-handle,

l' , at one end, for its operation, and carrying a small pinion, m , and a larger pinion, m' .

n is an intermediate shaft, having at one end a small pinion, n' , engaging with a gear-wheel, i^2 , on shaft i , and having at the other end a gear-wheel, n^2 , for engagement with the smaller pinion m on driving-shaft l . The shafts l n are sustained in suitable bearings above the press-box in the standards a . Shaft l is fitted for end movement in its bearing, so that its pinion m may be engaged with the gear-wheel n^2 on the intermediate shaft, and thus, through the gearing described, a slow and powerful movement downward be given to the follower; or the larger pinion m' of shaft l may be engaged directly with the gear-wheel i^2 of shaft i and a rapid upward movement be given to the follower.

The string-pieces b of the tramway are fitted with plates b' , set on edge, to serve as rails for trucks that carry the trays; or rails of any suitable character may be used.

C is a truck or carriage, consisting of a rectangular frame of suitable size, mounted on four flanged wheels, o , and provided with angle-irons p at the corners for retaining the trays in place.

The trays E are of usual character, being frames covered with wire-gauze, and fitted with cross-wires that sustain the gauze.

The trucks C are of a width to pass freely between the standards a of the press-box and of a height to sustain the gauze covering of the trays close to the discharge-apertures e' of the box.

In operation the potatoes or other vegetables will be first cooked by steaming or boiling, and the follower B being raised box A will be filled. The openings e' will be closed by slide f , and the driving-shaft l will then be turned to force the follower down and compress the mass in the box. When the desired pressure is obtained slide f will be opened and the follower, continuing to move down, will force the vegetables out upon the tray in streams. The force of the ejected streams will carry the tray and truck gradually forward until it is filled, when the slide f is to be closed until another tray and truck are brought up. The filled tray is ready for removal to the drying-house. These operations can be rapidly and conven-

iently performed, with a great saving of time and labor.

I do not limit myself to the details of construction exactly as described, as they may be varied within the scope of my invention.

Having thus fully described my invention, I claim as new and desire to secure by Letters Patent—

1. The press for preparing vegetables for dry-
ing, consisting of box A, having discharge-ap-
ertures e', the follower B, fitted for reciproca-
tion in the box, and the truck or carriage C,
carrying a tray and fitted for being passed be-
neath the press-box, combined substantially as
shown and described.

2. The combination, with a vegetable-press
having discharge-openings at the bottom, of
truck or carriage C and tray D, fitted for move-

ment on a track beneath the box, substantially
as shown and described.

3. In vegetable-presses, the box A, having a
bottom formed by inclined portion d and aper-
tured concave plate e, substantially as shown
and described.

4. The slide f, in combination with press-
box A, having the bottom aperture, e', sub-
stantially as and for the purposes set forth.

5. The follower B, racks h, operating-pin-
ions i, and friction-rollers k, combined together
and with box A, substantially as shown and
described, for operation as set forth.
